[57] CLAIM

We claim the ornamental design for image drum cartridge, as shown and described.

DESCRIPTION

FIG. 1 is a front view of image drum cartridge showing the new design;

FIG. 2 is a rear view of FIG. 1;

FIG. 3 is a top view of FIG. 1;

FIG. 4 is a bottom view of FIG. 1;

FIG. 5 is a left side view of FIG. 1;

FIG. 6 is a right side view of FIG. 1; and,

FIG. 7 is a perspective view of the image drum cartridge showing the new design.

The present article which is used for a copier or printer is an image forming unit for forming an image in an electrophotographic process. A toner image is formed by driving and charging an OPC drum, a developing roller, etc. while the present article is set in a predetermined position in the body of the copier or printer and supplied with power and high voltage electric source from the body. A concave portion for setting a toner cartridge is formed at the upper part thereof.
